UNITED STATES PATENT OFFICE.

LEWIS D. NELSON, OF COLDWATER, MICHIGAN, ASSIGNOR OF ONE-HALF TO ROBERT M. NEALE, OF UNION CITY, MICHIGAN.

FILLING MACHINE.

Application filed November 29, 1924. Serial No. 752,887.

This invention relates to improvements in filling machines.

My improvements are especially designed by me for filling bags with cement, lime and other heavy materials, and I have illustrated the same as embodied in a filling machine for handling cement.

My improvements are, however, readily adapted and desirable for use in numerous other relations.

The main objects of this invention are:

First to provide an improved bag filling machine which is automatic in its operation and is controlled by the weight of the filled bags.

Second, to provide an improved bag filling machine which may be easily operated, it only being required that the operator shall place the bags upon the filling spouts.

Third, to provide an improved filling machine for cement, lime and other heavy materials, which is not likely to become clogged.

Objects pertaining to details and economies of construction and operation of my invention will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

Fig. I is a fragmentary front elevation of a filling machine embodying the features of my invention, the upper portion of the hopper and the lower portion of the supporting frame and scale platform being broken away.

The machine illustrated is a duplex machine, or one having two filling and weighing mechanisms.

Fig. II is a fragmentary front perspective view.

Fig. III is a fragmentary view, mainly in section, on a line corresponding to line 3-3 of Fig. I.

Fig. IV is a fragmentary view partially in horizontal section on a line corresponding to the broken line 4-4 of Fig. III showing details of the feed means.

Fig. V is a fragmentary view partially in section to correspond with Fig. III with the ejector valve in closed position, it being shown in open position in Fig. III.

Fig. VI is a fragmentary front elevation showing details of the control mechanism.

Fig. VII is a fragmentary front elevation showing further details of the control mechanism.

60

Fig. VIII is a fragmentary view partially in section on a line corresponding to line 8-8 of Fig. III showing details of the discharge mechanism for the filled bags.

Fig. IX is a detail section on a line corresponding to line 9-9 of Fig. VIII.

Fig. X is a plan view of the scale beam.

Fig. XI is a detail front elevation of the scale platform.

Fig. XII is a fragmentary view partially in section showing details of the feed valve controlling means.

Fig. XIII is a detail view partially in section of a modified form of ejector in which a filling mechanism is provided at each side 75 of the ejector.

Fig. XIV is a fragmentary section showing the relation of the spout and the bag holder.

In the drawing the sectional views are 80 taken looking in the direction of the little arrows at the ends of the section lines and similar numerals of reference indicate similar parts throughout the several views.

Referring to the drawing, I provide a 85 main supporting frame 1 of suitable character to support the hopper 2 and the operating mechanisms. The structure shown in Fig. I is a double unit machine with the units arranged side by side, but as the units 90 are duplicates a description of one will be sufficient.

The material is supplied to the hopper 2 by any suitable means.

At the bottom of the hopper is a horizontally disposed ejector cylinder 3 having a central inlet port 4, there being a downwardly tapered mouth 5 leading to this port. Below the port is a conical port 6.

The rotor 7 has a disk-like body with a 100 conical central portion 8, the ejector blades 9 being mounted on the body of the rotor at the sides of the conical central portion 8. This conical central portion projects upwardly centrally of the conical port 6 which 105 provides a conical inlet above the blades. This conical port 6 is controlled by a conical valve 10 which has a conical recess in its under side to receive the apex of the conical portion of the rotor. The upper end of this 110

valve 10 projects into the mouth 5 of the cylinder. The valve 10 is automatically controlled by means which will appear in detail as the description proceeds.

5 The ejector cylinder is provided with a tangentially disposed passage 11. The rotor shaft 12 is disposed vertically projecting through the bottom of the cylinder 3. This shaft has a gear 13 at its lower end meshing 10 with the gear 14 on the driving shaft 15. The machine is controlled by a weighing mechanism which, in the structure illustrated comprises the scale beam 16 pivoted at 17 and provided with a weight 18. The 15 scale beam is also provided with an auxiliary scale rod 19 provided with an adjustable weight 20 for accuracy in adjustment.

Suspended from the scale beam is a platform carrying frame 21 having a yoke 22 engaging the pivot 23 on the scale beam. 20 The back 24 and sides 25 are fixedly mounted upon the scale frame or hangers providing a support for the bags open at the front.

To assist in placing and supporting the 25 bags, I provide a bag holder 26 which is mounted within the weighing machine walls to receive the rear portion of the bag indicated by dotted lines at 27 in Fig. III. The platform comprises a pair of sections 28 pivoted at 29 to the bottom of the bag holder. These platform sections are held yieldingly in erected position by means of the springs 30. These springs are adjusted to sustain a weight equal to approximately that of a 35 filled bag so that as soon as they are subjected to the entire weight of a filled bag the platform opens to discharge the bag.

The scale beam also carries a plate-like 40 spout carrier 31 which also constitutes a valve for the discharge port 11 of the ejector cylinder. This carrier 31 is mounted on the arm 32 of the scale beam, the carrier having a blade 34 riding on the scale beam arm as shown in Fig. VII.

45 The carrier 31 has an upwardly projecting arm 35 provided with a counterweight 36 for the carrier. The carrier is provided with a pair of spouts 37 pivoted at 38 and projecting forwardly above the scale platform, to 50 receive the bags 27. These spouts are held in erected position by the latches 39 mounted on the carrier, 31, the latches being disengaged by the trip arm 40, see Fig. III, the latches being alternately brought into coacting 55 relation with this trip arm as the carrier advances.

As the carrier moves downwardly with 60 the scale beam the latch is engaged by the trip arm and lifted from the coacting keeper 42 on the spout. A packing 43 is provided for closing the joint between the spout and the carrier, this packing projecting in the form of a nipple and the spout closing upon the same.

65 When the spouts are released by the bag,

which is of the valve type, slipping therefrom, the spouts are returned to erected position by means of the coiled springs 65. The latches 44 are held yieldingly in engaging position by means of the springs 46.

70 The bags are placed upon the spouts in inoperative position, or out of register with the discharge port of the ejector and are held in position by the latches 44 which are pivoted at 45 and held yieldingly in position by 75 means of the springs 46. The bag holders are arranged so that after a bag has been engaged therewith, pull upon the bag tends to clamp the bag holder until the spout tilts to release the bag, when it falls away from 80 the bag holder.

The carrier is automatically shifted or oscillated, its actuation being controlled by the movement of the scale beam so that upon the discharging of a filled bag the carrier is actuated to bring the other spout, having a bag thereon, into operative relation to the ejector, the carrier serving, as stated, as a valve for the ejector.

Above the carrier is a carrier actuating 90 lever 47 pivoted at 48 and provided with a roller 49 engaging the yoke 50 on the upper end of the carrier, the yoke having seats 51 at its ends adapted to receive the roller 49 when the carrier is at the extremes of its 95 strokes, the lever holding the carrier in this position. The lever is mounted upon the frame, while the carrier is, as stated, carried by the scale beam. The upward movement of the carrier on the scale beam swings 100 or tilts the carrier.

The actuating lever 47 is automatically shifted on the downward movement of the carrier by means of the links 52 which are connected to the lever at opposite sides of 105 its pivot and have a lost motion connection to the carrier. The links are slidably engaged with tappets 53 on the ends of the yoke 50.

110 It will be observed that as the carrier moves downwardly from its initial position, or the position in which it is supported when the scale beam is in its initial position, the tappet 53 on the side of the yoke, with which the roller is engaged as shown in Fig. VI, will engage the stop 54 on the coacting link, swinging the lever to its opposite position. The rollers are released from their seat in the yoke by the initial downward movement of the carrier.

115 This shifting of the lever and the vertical movement of the carrier causes its oscillation to bring first one spout and then the other into register with the discharge port 11.

120 To provide means for manually adjusting the carrier, the lever 47 is provided with a handle 55.

125 I provide a stop 56 which is pivoted at 57 at one end and adapted to be supported at the 130

other end by the rest 58. This stop has a rest 59 adapted to be alternately engaged by the stop pins 60 on the counterweight 36. As the carrier moves downwardly the stop pins are disengaged, allowing the swinging of the carrier, the stop 56, however, dropping down to engage the other stop pin, thereby positioning the carrier and relieving the carrier parts of shock as they are brought to rest at the end of the stroke.

I also provide the carrier with a pair of adjustable stop members 61 and 62 which alternately engage with the frame part 63. The stop 62 is shown in engagement with the carrier in the position shown in the left hand unit of Fig. 1 and the stop 61 is shown in engagement in the position shown in the right hand unit. The stop 62 has an in-turned or hooked outer end.

In order to prevent the packing of the material in the ejector cylinder during the time when the discharge passage is closed, I provide means for automatically closing the valve 10. The valve is connected to the arm 64 on the rock shaft 66 by means of the coupling 67, which engages the vertical stem 68 of the valve. This rock shaft projects to the outside and has an arm 69 longitudinally slotted at 70 to provide an adjustable connection to the valve actuating rod 71. The rod has a pin 72 adjustably engaged in the slot.

A spring 73 connected to the outer end of the arm 69 tends to hold the valve yieldingly open, thereby overcoming the tendency of the material within the cylinder to seat the valve. However, should the pressure of the material in the cylinder become excessive, as by the clogging of the discharge passage or from some other cause, the pressure of the material will close the valve 10, thus checking the feeding into the cylinder and prevent the roller becoming wedged or packed with material.

The valve rod 71 is actuated by means of the cam 74 on the tubular shaft 75, the cam having an abrupt drop at one side of its lift so that the valve is quickly released, the connecting rod being provided with a tappet 76 riding on the cam. The rod is slotted at 77 to engage the shaft 75 thereby retaining it in position.

The shaft 75 is driven with an intermittent movement to close the valve, as stated, during the shifting of the spout carrier member, during which period the discharge of the ejector is closed.

The mechanism for accomplishing this in the structure illustrated consists of the cam 78 which is connected to the shaft 75, the shaft 75 being supported on the shaft 79 having the ratchet wheel 80 thereon. The cam 78 is connected to this ratchet wheel by means of the pawl 81 which is pivoted on the cam at 82 and urged to engaging position by the spring 83. A pawl releasing or

tripping tappet 84 is adjustably mounted on the tripping lever 85 pivoted at 86. The lever has a downwardly projecting arm 87 resting on the arm 88 carried by the scale platform body.

As the scale platform or frame moves downwardly under the weight of the filled sack, the tripping tappet 84 is disengaged from the pawl, allowing the pawl to engage with the ratchet on the shaft 79, thereby driving the shaft 75 and closing the valve.

To insure a full stroke of the scale beam and associated parts, a cam 78 is arranged on the shaft 79 to coact with the lever 85, the lever 85 being provided with an adjustable arm 89 with which the cam engages. To prevent overthrow of the shaft 75 I provide a friction brake means consisting of a pair of brake arms 90 engaging a brake drum 91. These arms are supported by a rod 92 and the adjusting bolt 93. The shaft 79 is connected to the main driving shaft 15 by means of the vertically disposed transmission shaft 94 having a gear 95 thereon meshing with a worm 96 on the shaft 15. The shaft 94 has a gear 97 meshing with a gear 98 on the shaft 79.

In the modification shown in Fig. XIII the ejector cylinder 99 is provided with two tangentially disposed discharge passages 100 arranged on opposite sides of the ejector cylinder, there being a filling unit such as described on each side of the ejector.

My improved filling machine is of very large capacity, is automatic in operation, the operator merely being required to place the bags upon the spouts, and it is not likely to become clogged.

While the embodiment illustrated is especially designed for handling heavy material such as cement, my improvements are readily embodied or adapted for handling other materials. I have not illustrated certain other embodiments which I contemplate as I believe the disclosure made will enable those skilled in the art to embody or adapt my improvements as may be desired.

Having thus described my invention what I claim as new and desire to secure by Letters Patent is:

1. In a structure of the class described, the combination of an ejector cylinder provided with an inlet port opening centrally at the top thereof, a rotor provided with blades and having a deflector disposed centrally of said port, an upwardly seating inlet valve for said port, an arm on which said valve is rotatably mounted, the axis of the valve coinciding with that of the rotor shaft, a rock shaft by which said arm is carried, an actuating means for said rock shaft including a cam, a feed valve, a weighing mechanism, means for controlling said feed valve operatively associated with said weighing mechanism to be controlled thereby, and

- means for controlling the rock shaft actuating cam operatively associated with said weighing mechanism to be controlled thereby.
5. 2. In a structure of the class described, the combination of an ejector cylinder provided with an inlet port opening centrally at the top thereof, a rotor provided with blades and having a deflector disposed centrally of said port, an upwardly seating inlet valve for said port, a feed valve, a weighing mechanism, means for controlling said feed valve operatively associated with said weighing mechanism to be controlled thereby, and means for controlling the inlet valve operatively associated with said weighing mechanism to be controlled thereby.
10. 3. In a structure of the class described, the combination of a cylinder having an inlet port at the top thereof, a rotor, blades disposed on the upper side of said rotor, said cylinder having a tangentially disposed discharge opening in the horizontal plane of said rotor blades, an upwardly seating inlet valve for said port, a feed valve, a weighing mechanism, means for controlling said feed valve operatively associated with said weighing mechanism, and means for controlling said inlet valve operatively associated with said weighing mechanism.
15. 4. In a structure of the class described, the combination of a cylinder having an inlet port at the top thereof, a rotor, an upwardly seating inlet valve for said port, a feed valve, a weighing mechanism, means for controlling said feed valve operatively associated with said weighing mechanism, and means for controlling said inlet valve operatively associated with said weighing mechanism.
20. 5. In a structure of the class described, the combination of an ejector cylinder, an inwardly opening inlet valve therefor, means for closing said inlet valve permitting the normal floating movement thereof, whereby the undue filling of the cylinder tends to close the inlet valve, a discharge valve for said cylinder, a weighing mechanism, operating connections for said inlet valve to said weighing mechanism, and operating connections for said delivery valve to said weighing mechanism.
25. 6. In a structure of the class described, the combination of a cylinder, an inlet valve therefor, an ejector rotor for said cylinder, a discharge valve for said cylinder, a weighing mechanism, and operating connections for said valves to said weighing mechanism whereby the valves are closed upon the actuation of the weighing mechanism under load.
30. 7. In a structure of the class described, the combination of a cylinder, an inlet valve therefor, a rotor for said cylinder, a weighing mechanism, and operating connections
- for said valve to said weighing mechanism whereby the valve is closed upon the actuation of the weighing mechanism under load.
8. In a structure of the class described, the combination of a cylinder, an ejector rotor for said cylinder, a discharge valve for said cylinder, a weighing mechanism, and operating connections for said valve to said weighing mechanism whereby the valve is closed upon the actuation of the weighing mechanism under load.
70. 9. In a structure of the class described, the combination of a weighing mechanism including a scale beam, a carrier pivotally mounted on said scale beam for vertical and oscillating movement, a yoke on the upper end of said carrier having seats at opposite sides of said carrier pivot, a pivotally mounted actuating lever coacting with said yoke to actuate said carrier as the lever is actuated and hold it in its actuated position when said scale beam is in its initial position, a pair of links connected to said lever on opposite sides of its pivot, tappets with which said links have sliding engagement disposed at the ends of said yoke so that said lever is actuated to oscillate the carrier upon the movement of the scale beam, an arm on said carrier projecting above the carrier pivot, a counterweight on said arm, a pivotally mounted stop bar, a rest for the swinging end of said stop bar, stops on said counterweight coacting with said stop bar, said stops being disengaged by the downward movement of the scale beam, adjustable stops for the lower end of said carrier, and spouts mounted on said carrier to be alternately brought to receiving position.
80. 10. In a structure of the class described, the combination of a weighing mechanism including a scale beam, a carrier pivotally mounted on said scale beam for vertical and oscillating movement, a yoke on the upper end of said carrier having seats at opposite sides of said carrier pivot, a pivotally mounted actuating lever coacting with said yoke to actuate said carrier as the lever is actuated and hold it in its actuated position when said scale beam is in its initial position, a pair of links connected to said lever on opposite sides of its pivot, tappets with which said links have sliding engagement disposed at the ends of said yoke so that said lever is actuated to oscillate the carrier upon the movement of the scale beam, an arm on said carrier projecting above the carrier pivot, a counterweight on said arm, a pivotally mounted stop bar, a rest for the swinging end of said stop bar, stops on said counterweight coacting with said stop bar, said stops being disengaged by the downward movement of the scale beam, and spouts mounted on said carrier to be alternately brought to receiving position.
85. 11. In a structure of the class described,
90. 12. In a structure of the class described,
95. 13. In a structure of the class described,
100. 14. In a structure of the class described,
105. 15. In a structure of the class described,
110. 16. In a structure of the class described,
115. 17. In a structure of the class described,
120. 18. In a structure of the class described,
125. 19. In a structure of the class described,
130. 20. In a structure of the class described,

- the combination of a weighing mechanism including a scale beam, a carrier pivotally mounted on said scale beam for vertical and oscillating movement, a yoke on the 5 upper end of said carrier having seats at opposite sides of said carrier pivot, a pivotally mounted actuating lever coacting with said yoke to actuate said carrier as the lever is actuated and hold it in its actuated position when said scale beam is in its initial position, a pair of links connected to said lever on opposite sides of its pivot, tappets with which said links have sliding engagement disposed at the ends of said 10 yoke so that said lever is actuated to oscillate the carrier upon the movement of the scale beam, adjustable stops for the lower end of said carrier, and spouts mounted on said carrier to be alternately brought to receiving 15 position.
12. In a structure of the class described, the combination of a weighing mechanism including a scale beam, a carrier pivotally mounted on said scale beam for vertical and oscillating movement, a yoke on the upper 20 end of said carrier having seats at opposite sides of said carrier pivot, a pivotally mounted actuating lever coacting with said yoke to actuate said carrier as the lever is actuated and hold it in its actuated position when said scale beam is in its initial position, a pair of links connected to said lever on opposite sides of its pivot, tappets with which said links have sliding engagement disposed at the ends of said yoke so that said lever is actuated to oscillate the carrier upon the movement of the scale beam, and spouts mounted on said carrier to be alternately brought to receiving 25 position.
13. In a structure of the class described, the combination of a weighing mechanism including a scale beam, a carrier pivotally mounted on said scale beam for vertical and oscillating movement, a yoke on the upper end of said carrier, a pivotally mounted actuating lever coacting with said yoke to actuate said carrier as the lever is actuated and hold it in its actuated position when said scale beam is in its initial position, a pair of links connected to said lever at opposite sides of its pivot and having a lost motion connection to said carrier at opposite 30 sides of its pivot so that said lever is actuated to oscillate the carrier upon the movement of the scale beam, and spouts mounted on said carrier to be alternately brought to receiving position.
14. In a structure of the class described, the combination of a weighing mechanism including a scale beam, a carrier pivotally mounted on said scale beam for vertical and oscillating movement, a yoke on the upper end of said carrier, a pivotally mounted actuating lever coacting with said yoke to actuate said carrier as the lever is actuated and hold it in its actuated position when said scale beam is in its initial position, a pair of links connected to said lever at opposite sides of its pivot and having a lost motion connection to said carrier at opposite 35 sides of its pivot so that said lever is actuated to oscillate the carrier upon the movement of the scale beam, and spouts mounted on said carrier to be alternately brought to receiving position.
15. In a structure of the class described, the combination of a weighing mechanism including a scale beam, a feed control member pivotally mounted on said scale beam for vertical and oscillating movement, a yoke on the upper end of said feed control member, a pivotally mounted actuating lever coacting with said yoke to actuate said feed control member as the lever is actuated and hold it in its actuated position when said scale beam is in its initial position, a pair of links connected to said lever at opposite sides of its pivot and having a lost motion connection to said feed control member at opposite sides of its pivot so that said lever is actuated to oscillate the feed control member upon the movement of the scale beam, a counterweight for said feed control member, and stops for said counterweight, said stops being disengaged by the downward movement of the scale beam.
16. In a structure of the class described, the combination of a weighing mechanism including a scale beam, a feed control member pivotally mounted on said scale beam for vertical and oscillating movement, a yoke on the upper end of said feed control member, a pivotally mounted actuating lever coacting with said yoke to actuate said control member as the lever is actuated and hold it in its actuated position when said scale beam is in its initial position, and a pair of links connected to said lever at opposite sides of its pivot and having a lost motion connection to said feed control member at opposite sides of its pivot so that said lever is actuated to oscillate the feed control member upon the movement of the scale beam.
17. In a structure of the class described, the combination of a hopper, a feed means disposed below said hopper, an inlet valve for said feed means, a discharge valve for said feed means, a weighing mechanism including a platform frame, operating connections for said discharge valve to said weighing mechanism whereby the discharge valve is closed upon the actuation of the weighing mechanism, means for controlling said inlet valve comprising a valve actuating cam, a driving ratchet, a coacting pawl operatively connected to said valve actuating cam, a 130

5 pivoted lever provided with a pawl disengaging tappet, an arm on said platform engaging said lever, a cam operatively connected to said ratchet and coacting with said lever, and a friction brake operatively associated with said cams for preventing the overthrow thereof.

18. In a structure of the class described, the combination of a hopper, a feed means 10 disposed below said hopper, an inlet valve for said feed means, a discharge valve for said feed means, a weighing mechanism including a platform frame, operating connections for said discharge valve to said weighing mechanism whereby the discharge valve is closed upon the actuation of the weighing mechanism, means for controlling said inlet valve comprising a valve actuating cam, a driving ratchet, a coacting pawl operatively 15 connected to said valve actuating cam, a pivoted lever provided with a pawl disengaging tappet, an arm on said platform engaging said lever, and a cam operatively connected to said ratchet and coacting with 20 said lever.

19. In a structure of the class described, the combination of a hopper, a feed means disposed below said hopper, an inlet valve for said feed means, a weighing mechanism 30 including a platform frame, means for controlling said inlet valve comprising a valve actuating cam, a driving ratchet, a coacting pawl operatively connected to said valve actuating cam, a pivoted lever provided with 35 a pawl disengaging tappet, an arm on said platform engaging said lever, a lever actuating cam operatively associated with said ratchet and coacting with said lever, and a friction brake operatively associated with 40 said cams for preventing the overthrow thereof.

20. In a structure of the class described, the combination of a hopper, a feed means disposed below said hopper, an inlet valve 45 for said feed means, a weighing mechanism including a platform frame, means for controlling said inlet valve comprising a valve actuating cam, a driving ratchet, a coacting pawl operatively connected to said valve actuating cam, a pivoted lever provided with a pawl disengaging tappet, an arm on said platform engaging said lever, and a lever 50 actuating cam operatively associated with said ratchet and coacting with said lever.

21. In a structure of the class described, the combination of a hopper, a feed means disposed below said hopper, an inlet valve 55 for said feed means, a discharge valve for said feed means, a weighing mechanism, operating connections for said discharge valve to said weighing mechanism whereby the discharge valve is closed upon the actuation of the weighing mechanism, means for controlling said inlet valve comprising a valve actuating cam, a driving ratchet, a coacting 60 pawl

pawl operatively connected to said valve actuating cam, and means for controlling said pawl operatively associated with said weighing mechanism, and a friction brake operatively associated with said valve actuating cam for preventing the overthrow thereof. 70

22. In a structure of the class described, the combination of a hopper, a feed means 75 disposed below said hopper, an inlet valve for said feed means, a discharge valve for said feed means, a weighing mechanism, operating connections for said discharge valve to said weighing mechanism whereby the discharge valve is closed upon the actuation 80 of the weighing mechanism, means for controlling said inlet valve comprising a valve actuating cam, a driving ratchet, a coacting pawl operatively connected to said valve actuating cam, and means for controlling 85 said pawl operatively associated with said weighing mechanism.

23. In a structure of the class described, the combination of a hopper, a feed means disposed below said hopper, an inlet valve 90 for said feed means, a weighing mechanism, means for controlling said inlet valve comprising a valve actuating cam, a driving ratchet, a coacting pawl operatively connected to said valve actuating cam, means 95 for controlling said pawl operatively associated with said weighing mechanism, and a friction brake operatively associated with said valve actuating cam for preventing the overthrow thereof. 100

24. In a structure of the class described, the combination of a hopper, a feed means disposed below said hopper, an inlet valve for said feed means, a weighing mechanism, and means for controlling said inlet valve 105 comprising a valve actuating cam, a driving ratchet, a coacting pawl operatively connected to said valve actuating cam, and means for controlling said pawl operatively associated with said weighing mechanism to 110 be actuated by the movement of the weighing mechanism under load.

25. In a structure of the class described, the combination of a weighing mechanism, a feed means, an inlet valve for said feed means, 115 a discharge valve for said feed means, operating connections from said weighing mechanism to said discharge valve whereby the discharge valve is closed upon the actuation of the weighing mechanism, 120 means for controlling said inlet valve comprising an actuating cam, a driving ratchet, a coacting pawl operatively connected to said valve actuating cam, and a pawl control means operatively connected with said 125 weighing mechanism whereby the pawl is engaged with the ratchet upon the initial movement of the weighing mechanism.

26. In a structure of the class described, the combination of a weighing mechanism, a 130

- feed means, an inlet valve for said feed means, means for controlling said inlet valve comprising an actuating cam, a driving ratchet, a coacting pawl operatively connected to said valve actuating cam, and a pawl control means operatively connected with said weighing mechanism whereby the pawl is engaged with the ratchet upon the initial movement of the weighing mechanism.
27. In a structure of the class described, the combination of a weighing mechanism, a feed means, an inlet valve for said feed means, a discharge valve for said feed means, operating connections from said weighing mechanism to said discharge valve whereby the discharge valve is closed upon the actuation of the weighing mechanism, and means for controlling said inlet valve operatively connected to the weighing mechanism to be actuated by the movement of the weighing mechanism under load.
28. In a structure of the class described, the combination of a weighing mechanism including a scale beam, a control member pivotally mounted on said scale beam for vertical and oscillating movement, means for oscillating said control member actuated by the vertical movement thereof, means for insuring a full down stroke of the scale beam including a driving ratchet, a pawl operatively associated with said ratchet, a cam connected to said pawl to be driven therewith, a lever operatively associated with said cam and provided with a pawl disengaging tappet, and operating connections for said lever to said scale beam whereby the pawl is released on the initial movement of the scale beam and the cam is driven to insure the full stroke of the parts.
29. In a structure of the class described, the combination of a weighing mechanism including a scale beam, a platform frame carried thereby, a control member pivotally mounted on said scale beam for vertical and oscillating movement, means for oscillating said control member actuated by the vertical movement thereof, a driving ratchet, a pawl operatively associated with said ratchet, a cam connected to said pawl to be driven therewith, a lever operatively associated with said cam and provided with a pawl disengaging tappet, and an arm on said platform frame coacting with said lever.
30. In a structure of the class described, the combination of a weighing mechanism including a scale beam, an oscillating control member pivotally mounted on said scale beam, means for actuating said control member controlled by the vertical movement of said scale beam, a power means operatively associated with said weighing mechanism for insuring complete oscillation thereof on each actuation of the weighing mechanism, and a control for said driv-
- ing means whereby the same is actuated on the initial downward movement of the scale beam.
31. In a structure of the class described, the combination of a weighing mechanism including a scale beam, a control member pivotally mounted on said scale beam for vertical and oscillating movement, means for oscillating said control member actuated by the vertical movement thereof, and driving means for insuring a full down stroke of the scale beam adapted to be engaged by the initial movement of the scale beam.
32. In a structure of the class described, the combination of a weighing mechanism, a combined spout carrier and feed control member mounted on said weighing mechanism for oscillating and vertical movement, spouts mounted on said member to be alternately brought to operative position, a driving ratchet, a driven pawl operatively associated with said ratchet, a cam connected to said pawl to be driven therewith, a lever operatively associated with said cam and provided with a pawl disengaging tappet, and operating connections for said lever to said weighing mechanism to be actuated by the movement of the weighing mechanism under load.
33. In a structure of the class described, the combination of a weighing mechanism, a driving ratchet, a driven pawl operatively associated with said ratchet, a cam connected to said pawl to be driven therewith, a lever operatively associated with said cam and provided with a pawl disengaging tappet, and operating connections for said lever to said weighing mechanism to be actuated by the movement of the weighing mechanism under load.
34. In a structure of the class described, the combination of a weighing mechanism, an oscillating carrier supported by said weighing mechanism for vertical movement, means for oscillating said carrier controlled by the vertical movement thereof, spouts tiltingly mounted on said carrier to be alternately brought to operative position, a dumping platform operatively associated with said weighing mechanism, and a spring for yieldingly supporting said platform in erected position, the platform coacting with the spout to support the bags but being of insufficient strength to sustain the filled bags when they are discharged from the spouts.
35. In a structure of the class described, the combination of a weighing mechanism, a tiltingly mounted spout, means for releasing the spout operatively associated with the weighing mechanism, a dumping platform operatively associated with said weighing mechanism, and a spring for yieldingly supporting said platform in erected position, the platform coacting with the spout to support the bag but being of insufficient

strength to sustain the filled bags when they are discharged from the spout.

36. In a structure of the class described, the combination of a weighing mechanism including a dumping platform, a tilting spout, means operatively associated with said weighing mechanism for controlling the tilting of said spout, and a spring for

yielding'y supporting said platform in erected position, said spring being of insufficient strength to sustain the filled receptacle when discharged from the spout. ¹⁰

In witness whereof I have hereunto set my hand.

LEWIS D. NELSON.
